CLAIM

The ornamental design for a braiding hair rack as shown and described.

DESCRIPTION

FIG. 1 is a perspective view of a braiding hair rack showing my new design;

FIG. 2 is another perspective view thereof;

FIG. 3 is a front view thereof;

FIG. 4 is a back view thereof;

FIG. 5 is a left view thereof;

FIG. 6 is a right view thereof;

FIG. 7 is a top plan view thereof;

FIG. 8 is a bottom plan view thereof;

FIG. 9 is an enlarged view of a portion of the braiding hair rack shown within the area designated as 9 in FIG. 1;

FIG. 10 is an enlarged view of a portion of the braiding hair rack shown within the area designated as 10 in FIG. 1; and, FIG. 11 is an enlarged view of a portion of the braiding hair rack shown within the area designated as 11 in FIG. 2.

The evenly spaced broken lines depict portions of the braiding hair rack and form no part of the claimed design. The dot-dash broken lines encircling portions of the braiding hair rack in FIGS. 1-2 and illustrated in the enlarged views in FIGS. 9-11 form no part of the claimed design.
